UNITED STATES PATENT OFFICE.

HENRY GABRIEL GINACA, OF HONOLULU, TERRITORY OF HAWAII, ASSIGNOR TO
HAWAIIAN PINEAPPLE COMPANY, LTD., OF HONOLULU, TERRITORY OF HAWAII,
A CORPORATION OF THE TERRITORY OF HAWAII.

MACHINE FOR MARKING CANS.

1,066,488.

Specification of Letters Patent.

Patented July 8, 1913.

Application filed April 8, 1912. Serial No. 689,350.

To all whom it may concern:

Be it known that I, HENRY GABRIEL GINACA, a citizen of the United States, residing at Honolulu, county of Honolulu, Territory of Hawaii, have invented certain new and useful Improvements in Machines for Marking Cans; and I do hereby declare the following to be a full, clear, and exact description of the invention, such as will enable others skilled in the art to which it appertains to make and use the same.

This invention relates to machines for marking cans or other cylindrical containers, either before or after filling, in order that the grade of the contents of the can may be known after sealing.

The object of the invention is to produce a machine of this character which shall be automatic, continuous and efficient in operation.

Another object is to mark the can in two or three places on its periphery with similar type, so that at least one mark will always appear to view and thus obviate the necessity of turning the can in order to observe the marking.

Another object is to adapt the machine so that it can be quickly altered so as to mark the cans with a different mark or to mark cans of another size.

A further object is to provide means for marking cans which have been dented or are slightly out of round.

Machines have been made for marking either the top or bottom heads of cans while conveyed by a link belt or wire rope. The ordinary method, however, is to stamp the can by hand with a rocking motion of the rubber or other type on the cylindrical portion of the can, usually in a single place only, the marking indicating the contents of the pack, which is afterward covered by a suitable label.

With the above mentioned objects in view, my invention consists in the novel arrangement and construction of parts as hereinafter described and claimed, reference being had to the accompanying drawings, forming a part of this specification, in which corresponding parts in the several figures are designated by like characters of reference.

Figure 1 represents a side elevation of a machine for marking cans embodying my

invention in a preferred form. Fig. 2 is a similar view of a portion of the machine shown in Fig. 1, illustrating more fully the means for impressing the cans against the type wheel. Fig. 3 is a front elevation of the machine. Fig. 4 is a rear view of the machine. Fig. 5 is a sectional view on the line A—B of Fig. 1. Fig. 6 is an enlarged view of a portion of the face of the type wheel. Fig. 7 is a longitudinal section through the center of Fig. 6. Fig. 8 is a transverse section on the line C—D of Fig. 6. Fig. 9 is a plan view of the inking roller and the fork which supports the same.

Referring to the drawings, the body 1 of the machine is preferably a casting and provided with flanges 2 and 3 at its front and rear respectively for supporting the machine upon transverse wooden beams 4. In the bearing 5 at the top of the body 1 is journaled the shaft 6. A sprocket wheel 7 and a pulley 8 are secured to the shaft 6 on opposite sides of the bearing 5. The sprocket wheel 7 is provided with a sleeve or offset hub 9 on the side opposite to the bearing 5. A wheel 10 of wood or other suitable material is removably secured on the sleeve or hub 9 by means of the washer 11 and the nut 12, the end of the shaft 6 being threaded to receive said nut. A pin 13 in the sprocket wheel 7 engages a hole 14 in the wheel 10, so that this wheel is revolved with the shaft 6, Fig. 5. The wheel 10 is preferably provided with two flat traction rings 15 16 of rubber or other material, also with a plurality of rubber or other suitable type 17 secured at intervals between said rings to the periphery of this wheel, as shown. The thickness of the type 17 is greater than that of the traction rings 15 16, Figs. 7 and 8.

Two flexible bands 18 19 of rubber beltting or other suitable material are provided, their front ends being attached to the lug 20 of the body 1 and their rear ends to the lever 21 respectively. The lever 21 is fulcrumed on the pin 22 secured in the boss 23 of the body 1. The ends of a tension spring 24 are connected to the lever 21 and to a hook 25 in the bottom of the body 1, such that the bands 18 19 are normally tightened in a horizontal position, Fig. 1. The distance between the bands 18 19 and the wheel 10 is made less than the diameter

of the cans to be marked, in practice this distance being about three-quarters of the diameter of the can.

Suitable chutes are provided for receiving the cans to be marked and for discharging the cans when marked. Angle irons 26 27 are secured to the lugs 28 29 of the body 1 respectively. Frames 30 31 made of flat bars are fastened to the angles 26 27 respectively. Upper guard plates 32 33 and a side bar 34 are attached to and supported by the frames 30 31, as shown.

The ink roller 35 is mounted to turn on the pin 36 in the fork 37, Fig. 9. The fork 37 is provided with a hub 38 which is pivoted on the pin 39 secured to the boss 40 at the upper rear portion of the body 1, Figs. 1 and 4. The ink roller 35 rolls on the distributing roller 41 and on the type 17 on the wheel 10. The distributing roller 41 is attached to the sleeve 42 of the sprocket 43 which is mounted to turn on the pin 44 secured to the boss 45 of the body 1, Fig. 4. The sprockets 7 and 43 are connected by a link belt 46. The ink well 47 is secured by bolts 48 to the body 1, such that the roller 41 may revolve with a portion of said roller in ink in said well.

In operation the machine is driven in the direction as shown by arrows by means of a belt applied to the pulley 8. The cans to be marked roll down on the inclined angles 26 onto the flexible bands 18 19 and against the traction rings 15 16 on the wheel 10, which in revolving cause the can to continue rolling rearward, the flexible bands 18 19 being deflected from their normal horizontal position, and against the action of the spring 24, by the passage of the can or cans under the wheel 10, Fig. 2. During this passage under the wheel 10, however, the can has revolved about two-thirds of a revolution and has been successively impressed by two or three of the type 17 which have previously been inked by contact with the roller 35. The cans thus marked are pushed rearward by successive cans and are discharged from the machine by rolling down the inclined angles 27. The markings on the cans are not blurred by the adjacent cans, however, as the flanges of the heads prevent contact of the bodies with one another. The flexible bands 18 19 are placed far enough apart so as to clear the markings on the cans. Although the can may be dented or slightly out of round nevertheless the flexible bands 18 19 force the can against the type 17 and produce the desired markings on the can in not less than two places. When it is desired to change the mark, for example from the "B" grade as illustrated to some other grade or mark, the wheel 10 is easily replaced by a similar wheel with the desired type. When smaller cans are to be marked, a wheel 10 of a suitable larger

diameter and a slightly smaller ink roller 35 are employed, the change being easily and quickly made.

The cans may be fed to the machine either by hand or by a suitable conveyer in a well known manner.

While the machine has been described and illustrated for marking cans with their axes horizontal, it is obvious that the machine could easily be arranged to operate on cans whose axes are vertical.

I claim:

1. In a machine for marking cans and the like, the combination with a type wheel, of a trackway on which the cans are caused to roll while in engagement with said type wheel, said trackway comprising a flexible band fixed at one end, and means acting on the other end of said band to yieldingly oppose a deflection of said band by the cans.

2. In a machine for marking cans, the combination with a type-wheel, of a trackway on which the cans are caused to roll while in engagement with said type-wheel, said trackway comprising a flexible band fixed at one end, a movable element to which the other end is connected, and means acting on said element to exert a tensile stress on said band thereby tending to keep it taut.

3. In a can marking machine, a type-wheel, a support for the cans adapted to hold a plurality of cans in contact with the type-wheel, said support comprising a flexible band fixed at one end, a pivoted lever to which the other end of the band is connected and means acting on said lever and tending to turn it around its pivot to exert a continual tensile stress on said trackway.

4. A machine for marking cans comprising a type-wheel, traction rings on said type-wheel, type secured to the periphery of the type-wheel at intervals and adapted to mark the cans in two or more places, a stationary support for the cans adapted to hold a plurality of cans in contact with the type-wheel, and on which the cans are caused to roll by the traction rings on the type-wheel, said support comprising a flexible band spaced from the type-wheel a distance less than the diameter of the cans, and means acting on said band tending to keep it taut.

5. A machine for marking cans and the like comprising a type wheel, traction rings on said type wheel, type secured to the periphery of the type wheel at intervals, a stationary support for the cans adapted to hold a plurality of cans in contact with the type wheel and on which the cans are caused to roll by said traction rings, said support comprising a flexible band spaced from the type wheel a distance less than the diameter of the cans, and means acting on said band to yieldingly oppose a deflection thereof by the cans.

6. In a machine for marking cans and the like, a type wheel, traction rings thereon, type carried by said type wheel and located between said traction rings, a trackway on which the cans are caused to roll by said type wheel, said trackway comprising flexible bands spaced to straddle the markings on the cans, and means acting on said bands

to yieldingly resist a deflection thereof by the cans. 10

In testimony whereof I affix my signature, in presence of two witnesses.
